JENKINS VULCAN SPRING COMPANY, OF RICHMOND, INDIANA, A CORPORATION OF
INDIANA.

BENDING-MACHINE.

1,303,657.

Specification of Letters Patent. Patented May 13, 1919.

Application filed October 21, 1918. Serial No. 258,937.

To all whom it may concern:

Be it known that we, ERNEST J. GUEUTAL and THOMAS B. JENKINS, citizens of the United States, residing at Richmond, in the county of Wayne and State of Indiana, have invented a new and useful Bending-Machine, of which the following is a specification.

The object of our invention is to produce a machine for forming the leaves of leaf springs.

The accompanying drawings illustrate our invention. Figure 1 is a longitudinal vertical section of a machine embodying our invention, on line 1—1 of Fig. 2, and Fig. 2 a transverse section on line 2—2 of Fig. 1.

In the drawings, 10 indicates a suitable tank capable of containing a considerable quantity of tempering fluid, such, for instance, as oil. Extending transversely across tank 10 and supported in suitable bearings, is a shaft 11 carrying a polygonal work head 12, at each corner of which is provided a longitudinally-slotted frame 13, in which are slidably mounted several nuts 14 receiving adjustable abutment screws 15 which may be held in desired positions of adjustment by lock nuts 16. The several abutments 15 form supports for a pattern plate 17 which rests upon the several abutment pins 15 and is held in position at its center by a pin 18 carried by the middle screw 15 and passing through a suitable perforation in the pattern. The ends of the pattern are supported by clevises 19 which are adjustable lengthwise of the member 13 and are formed with a plurality of perforations, in a common manner, to receive the ends of the pattern 17 at various positions of adjustment.

Pin 18 has sufficient length to pass through a central perforation formed through the spring 20 which is to be formed.

Arranged upon each face of head 12 in alinement with each set of adjusting screws 15, is a set of independently slideable weights 21 held for sliding movement toward and from the pattern 17 by suitable guide bars 22, 23. Each of these weights 21 is formed at one end to engage and press upon the spring 20, these forming ends being preferably materially reduced in size so as to engage the springs 20 upon comparatively narrow transverse lines, as clearly indicated

in Fig. 2, so that the tempering oil may, in due course, thoroughly contact with the spring.

The center weight 21 and at least one weight at each side of the center weight, as indicated at 21', is provided with a V-shaped notch 21" in its working end, said notch at its mouth being slightly wider than the width of spring 20.

Each weight 21 is provided in one face with a notch 24 adapted to receive a latch bar 25 carried by arms 25' pivoted on the head 12 and normally urged to latching position by springs 26, 26. Notches 24 are so placed that, when bar 25 lies therein, the weights will be held at their most distant point relative to the companion pattern 17.

The level of oil in tank 10 is high enough to submerge each spring-forming unit when it is brought to its lowest position, but not high enough to submerge the spring 20 when it is brought to a substantially horizontal position, at which time the forming operation takes place.

Arranged in tank 10 is a suitable endless carrier 30 adapted to receive and deliver the completed springs. Shaft 11 may be either continuously driven at a suitable speed, or moved by a suitable step-by-step gearing. Arranged at a suitable point is a cam 31 adapted to engage arms 24' and withdraw latch bar 25 at about the time the corresponding set of weights 21 come to a vertical position above the companion pattern 17.

The operation is as follows: When each set of weights 21 has reached the position at the right of Fig. 1, they have dropped, or slid by gravity, to a position most remote from the companion pattern 17 and the adjacent latch bar 25 has dropped into notches 24. Continued rotation of head 12 brings the weights to and through the position shown at the top of Fig. 1 and from thence toward the position shown at the left of Fig. 1. Until arms 24' come into contact with cams 31, the weights will be held up and prevented from sliding toward the pattern 17 and at some time prior to this engagement, a suitably heated spring member 20 will be placed in position adjacent its pattern, being approximately held in position, if desired, by spring fingers 35 (Fig. 1). Just as the parts reach the position shown at the left

of Fig. 1, the latch bar 25 will be withdrawn, thus simultaneously releasing all the weights which are to be permitted to slide, and they descend by gravity upon the red-hot spring 20. The weights having bifurcated ends, will engage and straighten the spring relative to the pattern plate and the other weights will come into engagement with the spring and bend it downwardly upon the pattern, this bending action taking place successively beneath the various weights from the center outwardly lengthwise of the spring. The weights maintain their force upon the spring as head 12 rotates, and 15 the spring is brought into the tempering fluid. The pressure of the weights upon the spring is gradually reduced, due to the rotation of head 12, until the lowermost position shown in Fig. 1 is reached, 20 at which time there is substantially no force being exerted upon the spring. As the head 12 continues its motion, the weights will move gradually from engagement with the spring and about the time the 25 spring is ready to leave the tempering fluid, the weights will slide backwardly on head 12 so as to be retracted from the spring and the completed spring may then drop from the pattern and on to the carrier 30 by 30 which it will be discharged from the machine.

In the meantime, the operation just described has been successively carried on by the oncoming forming units. It will be 35 readily understood that the precise number of forming units to be carried by the head is not important, the number depending upon the shape and size of the head, the speed at which the machine is to be driven 40 and the rapidity with which the operators may supply the machine with properly heated spring pieces 20.

It will be noted that, by arranging the plane of movement of the weights 21 parallel with the horizontal axis of shaft 11, the necessity of any mechanism for causing relative movement between the pattern 17 and the weights 21 to obtain the necessary forming force to act upon the pieces 20, is entirely avoided.

In order that the weights may be individually locked against movement, so that those weights not required for bending short springs need not move, we provide bars 22 45 with perforations 40 opposite each weight 21 and each of the weights is provided with a corresponding perforation 41, so that locking pins 42 may be inserted and thus hold against movement those weights which are 50 not needed in any particular operation.

We claim as our invention:

1. A bending machine comprising a pattern member and a coöperating bending member, one movable toward and from the 55 other by gravity, and a support for said two

members movable about a horizontal axis, first to a position where the movable member will separate from the other member and then to a position where the movable member will approach the other member. 70

2. A bending machine comprising a pattern member and a coöperating bending member, one movable toward and from the other by gravity, a support for said two members movable about a horizontal axis 75 first to a position where the movable member will separate from the other member and then to a position where the movable member will approach the other member, and means for normally preventing the approaching movement. 80

3. A bending machine comprising a head rotatable about a horizontal axis, a plurality of bending units carried by said head, each of said bending units comprising a pattern member and a coöperating bending member, one movable toward and from the other by gravity, the movable member being so placed relative to the axis of the head that it will move alternately by gravity toward and from the other member, and means for normally preventing the approaching movement. 90

4. A bending machine comprising a head rotatable about a horizontal axis, a plurality of bending units carried by said head, each of said bending units comprising a pattern member and a coöperating bending member, one movable toward and from the other by gravity, the movable member being so placed relative to the axis of the head that it will move alternately by gravity toward and from the other member. 95

5. A bending machine comprising a head mounted to rotate about a horizontal axis, 100 and a plurality of bending units carried by said head in circumferentially spaced relationship, each of said bending units comprising a pattern member and a plurality of movable weights arranged lengthwise of the 105 pattern member and each movable toward and from the pattern member by gravity as the head swings about its axis. 110

6. A bending machine comprising a head mounted to rotate about a horizontal axis, a 115 plurality of bending units carried by said head in circumferentially spaced relationship, each of said bending units comprising a pattern member and a plurality of movable weights arranged lengthwise of the pattern member and each movable toward and from the pattern member by gravity as the head swings about its axis, and means for normally holding said weights against movement toward the pattern member. 120

7. A bending machine comprising a swinging head mounted upon a horizontal axis, a pattern member carried by said head, and a plurality of bending members arranged lengthwise of the pattern member, 125 130

said bending members being movable toward and from the pattern member as the head swings about its axis.

8. A bending machine comprising a swinging head mounted upon a horizontal axis, a pattern member carried by said head, a plurality of bending members arranged lengthwise of the pattern member, said bending members being movable toward and from the pattern member as the head swings about its axis, and means engaging said bending members for normally holding them against movement toward the pattern member.

15 9. A bending machine comprising a pattern member, a pivotal support for the article to be bent associated with said pattern

member, and a plurality of bending members arranged lengthwise of the pattern member and movable toward and from the pattern member, that bending member in alignment with the pivotal support, and a bending member longitudinally spaced from said last-mentioned bending member, having their working ends notched to straddle the article to be bent to straighten the same relative to the pattern as a preliminary to final bending.

In witness whereof, we have hereunto set our hands at Richmond, Indiana, this 16th day of Oct., A. D. one thousand nine hundred and eighteen.
